UNITED STATES PATENT OFFICE.

HERBERT W. C. TWEDDLE, OF PITTSBURG, PENNSYLVANIA.

IMPROVEMENT IN THE MANUFACTURE OF PARAFFINE AND PARAFFINE OILS.

Specification forming part of Letters Patent No. 99,975, dated February 15, 1870.

To all whom it may concern:

Be it known that I, HERBERT W. C. TWEDDLE, of the city of Pittsburg, in the county of Allegheny and State of Pennsylvania, have invented a new and useful Improvement in the Manufacture of Paraffine and Paraffine Oils; and I do hereby declare the following to be a full, clear, and exact description thereof.

My invention relates to the distillation of petroleum or other hydrocarbon oils, which can be made to yield a considerable percentage of paraffine; and consists in so carrying on the process of distillation that little or none of the paraffine will be decomposed, but most or all of it will pass over as vapor, and condense in the distillate, from which it may then be separated by cold and pressure.

Previous to the date of my invention, the efforts of oil-manufacturers were chiefly directed to securing from the crude oil the largest possible percentage of illuminating oil, in which oil the presence of paraffine was objectionable.

Since the early history of oil distillation, a fire-heat of high temperature has been commonly applied to the outside of the still. When from forty-five to sixty per centum of the oil was thus distilled over, the distillate marked 43° or 44° Baumé hydrometer, and was yellow in color and objectionable in odor.

In order to obviate these objections, various devices were adopted, such as high domes, goose-necks, &c., the immediate object being to decompose the heavier oils, which contained the paraffine, and prevent them from passing over into the condenser, as a result of which change the product was made lighter, both in gravity and color. By the use of such appliances, the vapors of the heavier oils, which contain the paraffine, are condensed in the dome or goose-neck and fall back into the still, where they are decomposed by the high and destructive temperature of the fire, a part going over and being condensed into light illuminating oil, almost colorless, and a part forming carbides of hydrogen or other non-condensable gases and water, and another portion being precipitated or adhering to the sides or top of the still as solid carbonaceous matter. The residuum left in the stills as the result of

such process of distillation (of which residuum the carbonaceous matter last referred to forms a large part) amounts to from three to ten per cent. of the oil distilled, and which sometimes exists in a tarry mass, or may be reduced to a coke. If this residuum be distilled rapidly by fire-heat in large quantities, it will produce oils from 43° gravity down to 24° or 20° Baumé, which oils, when chilled and submitted to pressure, yield from eight and one-half to twelve pounds of pure paraffine per barrel of residuum, or from forty to sixty pounds per one hundred barrels of crude petroleum. Such paraffine so produced is at first of a dark olive green color, and the oil pressed out is heavy, of offensive odor, and has a characteristic blue or green color. Then a subsequent severe and expensive chemical treatment is required to decolorize both the paraffine and oil, and to somewhat deodorize the oil.

After being thus purified such oils are used as lubricants; but they are very deficient in body, and contain animal or vegetable oils, which compounds assume, to a great extent, the blue and green tint above referred to, which, in commerce, is objectionable, and paraffine oils thus made do not command a ready sale for the above reasons.

My improved mode of producing paraffine and lubricating oil is, as a process, directly the reverse of that above described. Instead of decomposing the paraffine, I so carry on the distillation as to prevent such decomposition as far as possible. In this process I distil with a comparatively low heat produced by free steam superheated or not at pleasure in a vacuum, or a partial vacuum, with or without a fire on the outside of the still, by which means I am enabled to produce paraffine in large quantity, and a superior quality of lubricating-oil, both of which are of marketable quality, and in fit condition for use, requiring but little further chemical treatment.

To enable others skilled in the art to make use of my invention, I will proceed to describe the same.

The crude petroleum or other hydrocarbon, having first been deprived of its lighter ingredients, such as gasoline, benzine, &c., by steam distillation or otherwise, is admitted into a vacuum-still of such construction as to

permit the vapors of distillation to flow over freely, or be drawn over, so that they shall not condense before leaving the still.

By a perforated pipe, or in other suitable manner, I admit steam, common or superheated, into the body of the still, keeping up at the same time, by suitable appliances, a partial or nearly complete vacuum. In connection with the steam-heat a moderate fire-heat may be applied to the outside of the still in any of the ways known to the art. The process of distillation is carried on till from thirty-eight to forty-eight percent. of the crude material is driven off, which being condensed gives illuminating-oil as a product, at which point the distillation shows a gravity of about 37° or 38° Baumé. The contents of the still will then have a gravity of from 28° to 35° Baumé, and contain a large percentage of paraffine. The distillate is then drawn off into another receiver. The distillation is then continued with a comparatively low heat, so that the heavier ingredients of oil shall not be decomposed, but being vaporized shall pass over freely or be drawn over into the condenser. The process is carried on as long as any yield of paraffine vapor can be obtained. It will be found that the condensed product becomes richer and richer in paraffine as the distillation goes on. The condenser must be kept warm while this is going on, or the paraffine will solidify and clog the apparatus. After the distillation is finished, and paraffine ceases to come over, the residuum will be found to contain very little paraffine. The distillation is then chilled and pressed. The oil being expressed there remains paraffine of a good color, requiring very little further treatment previous to use. Commonly remelting, rechilling, and repressing will suffice to remove all deleterious or objectionable impurities, and produce a pure article of paraffine. In this way I obtain from eight to sixteen pounds of almost chemically pure paraffine per barrel of crude petroleum, the chief reason of this larger yield being that in this process the paraffine vapors are formed by a comparatively low temperature, carried over freely, and condensed without being decomposed in the still.

The oils which, in the process described, are expressed from the paraffine product are for lubricating purposes vastly superior to the

lubricating oils produced by the tarry residuum of the old process, or if made direct from petroleum by direct fire. Though of less gravity, averaging 30° to 35° Baumé, they have a much better body. They have but a slight pungent odor, which is easily and almost wholly removed by a slight subsequent chemical treatment, and have hardly a trace of the blue or green tint which is a distinctive characteristic and an objectionable feature of lubricating-oils made by the ordinary process. The almost entire absence of the blue and yellow tint and offensive odor renders this oil, which I have introduced in commerce as neutral topaz oil, much more valuable than the lubricating-oils produced by distilling tar or petroleum, or other hydrocarbon, by the first process hereinbefore described and in general use. The lubricating-oil thus described is a specific product of this mode or process of manufacture, and cannot be made in any other way. By the qualities specified it is readily distinguishable, by any one skilled in the art, from all other lubricating oils heretofore known to the trade.

What I claim as my invention, and desire to secure by Letters Patent, is—

1. The process of producing paraffine, hereinbefore described, by an exhaustive distillation of the heavy oil at a comparatively low temperature, by the use of steam in a vacuum-still, with or without a fire-heat, so as to drive over the paraffine vapors undecomposed, substantially as described.

2. The production, by the process hereinbefore described, of a lubricating-oil as a new article of manufacture, possessing the distinctive and distinguishing features above set forth, viz., almost entire freedom from the blue and green tints which characterize the paraffine oils of commerce.

3. The use, in the distillation of oil, of a vacuum or partial vacuum, in connection with steam, common or superheated, inside the still, and an auxiliary fire outside, substantially as described.

In testimony whereof I, the said HERBERT W. C. TWEDDLE, have hereunto set my hand.

HERBERT W. C. TWEDDLE.
